No. 13,514

JAN 9, 1883

UNITED STATES PATENT OFFICE.

H. CLAY BASCOM AND CYRUS A. HODGES, OF TROY, AND TOBIAS S. HEISTER, OF LANSINGBURG, ASSIGNEES TO N. S. VEDDER PATTERN WORKS, BASCOM, GALBRAITH & CO., OF TROY, NEW YORK.

DESIGN FOR A STOVE.

SPECIFICATION forming part of Design No. 13,514, dated January 9, 1883.

Application filed November 17, 1882. Term of patent 7 years.

To all whom it may concern:

Be it known that we, H. CLAY BASCOM and CYRUS A. HODGES, each a citizen of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for Stoves, of which the following is a specification, reference being had to the accompanying cut, print, or engraving of a stove having said new design.

The design for the vase is not a part of this invention.

The design for the panel A consists of the compound floral ornament *a*, surrounded by the border *b*, having angles in its top and bottom, large arcs in its sides, and small arcs in its corners, all shaped and arranged substantially as shown in the aforesaid print.

The design for the plates B of the upper section consists of the panel A, composed of the ornamental parts *a* and *b*, as above described, the outer ornamental border, *c*, and the ornamented diagonal band *d*, all shaped and arranged together substantially as shown in the accompanying cut.

The design for the plate C of the combustion-chamber section consists of the upper panels, *e*, and lower panels, *f*, having the ornaments *g*, and surrounded by the ornamented bars *h*, all shaped and arranged together substantially as represented in the aforesaid engraving.

The design for the fire-pot section D consists of the upper portion, *i*, having the open-work ornamentations *j* and the lower portion, *k*, having the open-work ornamentations *l m n*, all shaped and arranged together substantially as shown in the aforesaid print.

The design for the side plate, E, of the ash-pit section consists of the semicircular bottom ornament, *o*, standing ornaments *p*, connecting base-bar *q*, arch *r*, series of rosettes *s*, and or-

naments *t*, all shaped and arranged substantially as shown in the aforesaid engraving.

The design for the door F consists of the semicircular ornaments *o'*, standing ornaments *p'*, and inclined leaf-form ornaments *u*, shaped and arranged substantially as shown in the aforesaid cut.

The design for the legs consists of the upper ornamental arc, *v*, lower united arc, *w*, plume ornaments *x*, and star ornaments *y*, all shaped and arranged substantially as shown in the aforesaid print.

What we claim as our invention is—

1. The design for the panels A, composed of the parts *a* and *b*, shaped and arranged as set forth.

2. The design for the plates B, consisting of the panel A, composed as described, in combination with the parts *c d*, shaped and arranged as set forth.

3. The design for the plate C, composed of the parts *e f g h*, shaped and arranged together as described.

4. The design for the fire-pot section D, composed of the parts *i j* and *k l m n*, shaped and arranged together as set forth.

5. The design for the plate E, composed of the parts *o p q r s t*, shaped and arranged together as set forth.

6. The design for the door F, composed of the ornaments *o' p' u*, shaped and arranged as described.

7. The design for the legs, composed of the parts *v w x y*, shaped and arranged together as set forth.

In testimony whereof we hereunto set our hands, in the presence of two subscribing witnesses, this 14th day of November, 1882.

H. CLAY BASCOM.
CYRUS A. HODGES.
TOBIAS S. HEISTER.

Witnesses:

AUSTIN F. PARK,
FRANCIS RITCHIE.
